FIG. III.

UNITED STATES PATENT OFFICE.

PHILIP WUEST, JR., OF PHILADELPHIA, PENNSYLVANIA, ASSIGNOR TO THE AUTOMATIC PIANO ACTION COMPANY, OF PHILADELPHIA, PENNSYLVANIA, A CORPORATION OF NEW JERSEY.

NOTE-SHEET.

1,111,121.

Specification of Letters Patent. Patented Sept. 22, 1914.

Application filed May 17, 1904. Serial No. 208,370.

To all whom it may concern:

Be it known that I, PHILIP WUEST, Jr., of Philadelphia, in the State of Pennsylvania, have invented certain new and useful 5 Improvements in Note-Sheets, whereof the following is a specification, reference being had to the accompanying drawings.

My invention relates to perforated webs or sheets of paper, or like material, arranged 10 to control the operation of a mechanical musical instrument, as for instance, a piano player, by being progressed over a pneumatic tracker bar provided with a series of apertures leading to respective motor valves. 15 Such an instrument is provided with a tempo controlling device, usually comprising a lever arranged to traverse a tempo scale having numbered graduations.

As heretofore constructed sheets of the 20 class specified are not provided with any indications of the measures or other time divisions of the musical composition represented therein, and therefore it requires a skilled operator to play, with such sheets, 25 any composition requiring recognition of such divisions, for instance, solo accompaniments.

It is the object of my invention to provide a note sheet with indications, upon its face, 30 determining the precise regions thereof corresponding with the pulses of the musical composition, so that even an unskilled operator may be apprised thereof, in advance of the registry of the same with the tracker 35 bar of the instrument which is being played, and, be thus enabled to control the operation of the instrument in proper time with the independent rendition of a solo.

As hereinafter described my invention 40 provides a sheet of the class specified with rhythm indicators comprising lines extending transversely with respect to its length, which lines are located at the regions of the sheet corresponding with the pulses in the 45 musical composition, although they may be irregularly spaced in reference to the length of said sheet, it being understood that there is no uniform relation between the length of such a sheet and the location of pulses in the composition represented by it; the 50 distance between the adjoining rhythm indicating marks being varied in accordance with the tempo of the composition.

My invention also comprehends such ar-

rangements of the rhythm indicators aforesaid, that they may also indicate the correct position of the tempo controlling device, either by an interruption in their transverse length corresponding with the determined position of said device, or by a symbol, associated with said lines, manifesting such position.

My invention comprises the various novel features of construction and arrangement hereinafter more definitely specified and 65 claimed.

In the accompanying drawings, Figure I, is a plan view of a fragment of a note sheet, conveniently embodying my invention. Figs II and III, are plan views of fragments of note sheets showing modified forms 70 of my invention.

In the form of my invention shown in Fig. I, the note sheet 1 is provided with perforations 2, representing the musical 75 composition, and the transverse lines 3, and 4, respectively indicating the accented and unaccented pulses of the rhythm. Said lines 3, may be broader than the lines 4, to distinguish the accented pulses from those 80 which are not accented, or such distinction may be otherwise made; for instance, by forming said lines of different colors.

In the form of my invention shown in Fig. II; the lines 3, and 4, are provided with 85 symbols 6, indicating variations in tempo, contemporaneous with the respective pulses; the numerals marked in the circles corresponding with the numerals on the tempo 90 scale of an ordinary musical instrument with which said sheet is adapted to coöperate.

In the form of my invention shown in Fig. III; the symbols 8, indicating the tempo, are located in the lines 3, and 4, transversely with respect to the sheet, in definite 95 relation to the corresponding position of the tempo controlling device indicated by the numerals marked within the circles of said symbols.

In order to mark sheets in the manner indicated in the several figures, I find it convenient to provide a master note sheet roll with marginal apertures 10, 11, shown in Fig. III, in registry with the respective 105 rhythm lines 3, and 4, which apertures are arranged to uncover a pneumatic duct or ducts controlling a suitable marking or

printing mechanism, when such a sheet is progressed over a tracker bar operatively connected therewith.

Although said marginal apertures 10, 11, 5 are conveniently formed as open notches, it is to be understood that they may be circular perforations similar to the perforations representing the musical composition.

A sheet constructed in accordance with 10 my invention is used as follows: The sheet being mounted in a suitable musical instrument and the sheet thereon being progressed over the tracker bar, the different pulses of 15 the rhythm of the musical composition being played are indicated in precise time by the successive registry of the lines 3, and 4, either with the apertures in the tracker bar, or with an auxiliary device comprising an index point, for instance, the circle 12, in 20 the field 13, carried by the arm 14, indicated in Fig. I, and the operator is thus enabled to note the approach of the lines indicating accented and unaccented pulses to the tracker bar, and the exact moment of registration 25 of said lines with the apertures of the tracker bar. By the information thus afforded, even an unskilled operator can be apprised of the proper period at which to manipulate the tempo and expression controlling devices, so as to correctly reproduce a given 30 musical composition, or what is even more difficult, to play an accompaniment with the proper emphasis and in proper relation to a solo played or sung by another person.

35 Moreover, such indications of the pulses of the measure in the improved sheets enable the operator to control the loud pedal mechanism more intelligently than with ordinary sheets.

40 It is to be understood that the arm 14, may be operatively connected with the tempo controlling device, so that as the transverse rhythm lines 3, and 4, are successively presented in registry with the circle 12, in the 45 field 13; said arm 14, may be shifted transversely in accordance with the tempo symbols associated with said lines, and thus ef-

fect the indicated variations in the tempo with proper relation to accented or unaccented pulses of the music.

50

I do not desire to limit myself to the precise details of construction and arrangement herein set forth, as it is obvious that various modifications may be made therein without departing from the essential features of my 55 invention.

I claim:

1. A note sheet for self-playing musical instruments having apertures arranged in longitudinal sequence thereon for controlling the playing devices, said sheet having transverse lines of different character alternately arranged thereon, said lines being located on said sheet in such relation to said apertures as to accord with the accented and unaccented impulses of the music respectively, and also in such relation to a predetermined point in the field of vision of the operator that said lines when passing said point indicate to the operator the proper period at which to manipulate the controlling devices in accordance with said accented and unaccented impulses of the music.

2. A note sheet for self-playing musical instruments, having apertures arranged in longitudinal sequence thereon for controlling the playing devices, and having transverse lines of different character alternately arranged and located with relation to said apertures in accordance with the accented and unaccented pulses of the music, and also having symbols arranged upon said lines, to designate the successive positions of the speed controlling mechanism proper for correspondence with said pulses, substantially 85 as set forth.

In testimony whereof, I have hereunto signed my name at Philadelphia, Pennsylvania, this fourteenth day of May, 1904.

PHILIP WUEST, JR.
